(57) **CLAIM**

We claim the ornamental design for a sound processor, as shown and described.

DESCRIPTION

The present application is also related to U.S. patent application Ser. No. 29/381,368, filed on Dec. 17, 2010, entitled “Sound Processor” to James P. Goodman et al., which is incorporated herein by reference in its entirety.

FIG. 1 is a perspective view of a sound processor showing our new design;

FIG. 2 is another perspective view thereof;

FIG. 3 is a front view thereof;

FIG. 4 is a rear view thereof;

FIG. 5 is a side view thereof;

FIG. 6 is another side view thereof;

FIG. 7 is a top view thereof;

FIG. 8 is a bottom view thereof; and,

FIG. 9 is an exploded perspective view thereof.

The portions of the sound processor shown in broken lines do not form part of the claimed design.
